UNITED STATES PATENT OFFICE.

GEORGE A. RIPLEY, OF DALLAS, TEXAS.

REVERSIBLE CUFF.

Application filed March 5, 1921. Serial No. 449,844.

To all whom it may concern:

Be it known that I, George A. Ripley, a citizen of the United States, residing at Dallas, in the county of Dallas and State of Texas, have invented certain new and useful Improvements in Reversible Cuffs, of which the following is a specification.

This invention relates to new and useful improvements in reversible cuffs.

10 The invention has particularly to do with a cuff which folds upon itself and is commonly known as a "French" cuff. The particular object of this invention is to provide a cuff which is reversible and permanently attached to the sleeve so that it may be turned to present a fresh side when one side has been soiled, and to make said cuff in a new and novel manner, whereby the labor involved is reduced and the cuff is more simply and expeditiously made at a minimum cost.

A construction designed to carry out the invention will be hereinafter described together with other features of the invention.

25 The invention will be more readily understood from a reading of the following specification and by reference to the accompanying drawings, in which an example of the invention is shown and wherein:

30 Fig. 1 is a perspective view of a cuff constructed in accordance with my invention and folded outwardly upon itself in the usual manner.

Fig. 2 is a similar view with the cuff reversed, or folded inwardly.

Fig. 3 is a vertical sectional view on an enlarged scale taken on the line 3-3 of Fig. 1, and

Fig. 4 is a plan view illustrating the manner of uniting the end of the sleeve with the divided sections of one face of the cuff.

In the drawings the numeral 10 designates a sleeve of a shirt or the like to which the cuff is attached. The first operation in making the cuff is of great importance as it saves considerable time and makes for convenience as well as a reduction in the cost. The lower edge of the sleeve 10 is flattened out and placed between a narrow

50 strip 11 and a wider strip 12 of fabric from which the cuff is to be formed. As shown in Fig. 4, the edges of the three pieces of material are brought into registration so as to aline along their lower edges. These three parts are united by a single row of 55 stitches 13. The edges of the sleeve 10 are

folded inwardly so that the side edges or ends of the strips 11 and 12 will overhang the sleeve on each side.

The section 12 is turned down so as to depend from the lower end of the shirt sleeve, while the section 11 is retained in its overlapping position. The distance from the upper edge of the section 11, to the lower edge of the section 12 is the length of the cuff and, therefore, it is only necessary to cut a piece of lining 14 and a piece of fabric 15 and place the same on the sections 11 and 12 so that the lining is outside of the fabric 15 and the sleeve 10 is between the section 11 and the fabric 15, which latter forms one face of the cuff. By stitching the sections and the parts 14 and 15 together as at 16, except along the top edges of the cuff where the section 11 alines with the upper ends of the parts 14 and 15, the cuff is ready to turn.

After the parts have been united the cuff is turned or inverted. When the cuff is turned the lining 14 will be inside and between the facing 15 and the facing formed by the sections 11 and 12. The cuff is completed by stitching around all four edges with a row of stitching 16 which gives the cuff a finish and also unites the top edges. It will be seen that the operation of making is very simple and a very neat cuff is had.

When the cuff is folded as shown in Fig. 3, the face formed by the section 12 will be exposed in the usual manner. If this face becomes soiled the cuff may be folded inwardly as shown in Fig. 2, whereby the face 15 is exposed. The cuff when folded in either position has a neat and regular appearance.

The manner of making the cuff is of great importance. By directing the section 11 upwardly parallel with the sleeve a fold of the goods is eliminated and consequently the only fold had where the cuff is attached to the end of the sleeve is the fold of the section 12. This makes a much neater cuff and obviates the tendency to form a ridge along this point.

Various changes in the size and shape and modifications may be made without departing from the spirit of the invention.

What I claim, is:

1. The method of producing a reversible cuff which consists first in sewing the lower edge of a shirt sleeve between a short section and a long section of fabric by a single row of stitches, second spreading the sections out

in opposite directions, third securing to the sections of fabric a cuff facing and a lining; fourth inverting the parts by turning the cuff structure upon itself, and fifth uniting 5 the edges of the sections and cuff facing fabric.

2. A sleeve having a cuff comprising a ply entirely free from the sleeve, said ply having a portion always around the outside of the 10 sleeve and another foldable portion adapted to extend within the sleeve or outside of the sleeve and of said first named portion a ply between the outside of the sleeve and the inside of the first named portion of the first named 15 ply, stitched to the adjacent free edge of the latter and to the free end of the sleeve, and a third foldable ply stitched at one edge to said free end of the sleeve by the same stitching that attaches the second named 20 ply to the sleeve, the third named ply extending along the foldable portion of the

first named ply and stitched to the free edge of the latter.

3. A sleeve having a cuff comprising a foldable ply extending between the extreme 25 edges of the cuff, a foldable ply lapping the first named ply and stitched to and extending from one of said edges to a point distant from the other edge, and a third ply stitched to the other of said first named edges and 30 lapping along a portion of the first named ply, between the sleeve and said first named ply, the second and third named plies being stitched along their inner edges to the end 35 portion of the sleeve by the same stitching leaving the third named ply and a portion of the first named ply free around the exterior of the sleeve, said cuff having two button holes adjacent to each end beyond the sleeve adapted to register.

In testimony whereof I affix my signature.
GEORGE A. RIPLEY.
